UNITED STATES PATENT OFFICE

2,175,578

POWER DEVICE

William E. Stout, Los Angeles, Calif.

Application March 22, 1939, Serial No. 263,491

1 Claim. (Cl. 74—125)

The object of my invention is to provide a novel and effective power device primarily for use on airplanes and submarines, and especially to provide a power device which will eliminate the hazard of gasoline motors in airplanes and submarines and substitute for them an electro-mechanical power plant. It is also within the contemplation of my invention to utilize my power device for obtaining increased power in connection with other machinery or devices other than airplanes and submarines.

I attain these and other objects of my invention by the apparatus illustrated in the accompanying drawing, in which—

5 Figure 1 is a somewhat diagrammatic top plan view of the device;
Fig. 2 is an enlarged detail view, partly in side elevation and partly in section of my power multiplying lever mechanism.

0 Like numerals designate like parts in each of the several views.

Referring to the accompanying drawing, I provide an electric motor 1, electrically connected with a suitable battery 2. The drive shaft 1a of motor 1 carries a pinion 3 meshing with the end gear 4 of the spring cylinder 6. Spring cylinder 6 in turn drives the bevel gear 13 meshing with the gear 14 on shaft 15, which shaft in turn carries a bevel gear 16 meshing with bevel gear 17 on a shaft 18.

The shaft 18 carries a series of eccentrics or cams 19, each of which engages a roller 20 carried by a vertically extending rod 21. Shaft 21 is mounted in a suitable vertical guide 22, as shown in Fig. 3. Rod 21 is operatively connected by a pin or other suitable member 23 with a lever 24.

Each of the several levers 24 are pivotally mounted at 25 on a pivot support 26, which support is preferably a fixed support, but may be a flexible support if desired, or found more advantageous. The end 27 of each of the several levers 24 successively enter the corresponding successive slots 28 of the slotted roller 29, said roller being mounted on a suitable shaft 30, as shown in Fig. 3.

As there are a series of levers 24 successively operating to engage the roller at the slots 28, a continuous rotation of the roller will be produced due to the successive action of levers successively thrown into operation engaging the roller. The rotation of the roller 29 also rotates its power 10 shaft 30 which may drive the propeller on airplanes or submarines.

I may, if desired, provide end guides for the outer ends of each of the levers 24. The said guides may be fixed if the support 26 is a fixed support; or the guides may be movable if the supports 26 are flexible supports, to cause the operating end 27 to be successively inserted in and withdrawn from the slots 28 of roller 29, if such construction is found advantageous.

What I claim is:

In a power device, the combination of a driven shaft, eccentrics mounted on said shaft, rods driven by said eccentrics, guides for said rods, levers operatively connected to said rods, a roller having a series of slots to permit the operating end of the aforesaid levers to engage in said slots, said series of slots being staggered to permit of successive actuation of the roller by the aforesaid levers, and a power transmitting shaft on 15 20 25 30 35 which said roller is mounted.

WILLIAM E. STOUT.
